FIG. 3

Patented Jan. 3, 1928.

1,654,654

UNITED STATES PATENT OFFICE.

ROSCOE C. KIRWIN, OF CORAOPOLIS, PENNSYLVANIA.

APPARATUS FOR TREATING HYDROCARBON LIQUIDS.

Application filed October 9, 1925. Serial No. 61,454.

My invention relates to improvements in methods of and apparatus for producing gasoline or similar relatively light hydrocarbons from crude petroleum or from various products of crude petroleum.

The general object of my invention is to treat the heavier hydrocarbons, such as crude oil and kerosene, in such manner as to produce a greater quantity of the more valuable light hydrocarbons, such as gasoline, than has been possible to produce by the cracking methods heretofore employed.

Another object of my invention is to provide an improved means and a method whereby cracking of heavy hydrocarbons may be effectively accomplished, without the necessity of placing said hydrocarbons under pressure.

Another object of my invention is to provide means for more effectively controlling the temperature to which hydrocarbons are subjected during the cracking operation and thereby secure a maximum percentage of gasoline and the like, and also to prevent formation and precipitation of carbon within the cracking zone.

It has been common practice heretofore to heat crude oil under pressure to effect cracking thereof. This method results in the formation of unsaturated hydrocarbon gases that must be withdrawn from the system, since they cannot enter into and form part of the body of gasoline. These gases are sometimes employed in burners under a still but, when used as fuel, are of less value than if incorporated in the gasoline.

Pressure systems are also unsatisfactory owing to the difficulty of maintaining proper pressures and temperatures, with the result that explosions are of frequent occurrence and the vapors often become overheated and burn, thereby involving loss and also causing a deposit of carbon within the system.

Not only are these objectionable features minimized by my system, but I eliminate the necessity of employing extra apparatus such as expansion chambers and various control valves, etc., which are required in pressure systems.

Referring to the accompanying drawing, Fig. 1 shows, diagrammatically, a system to which my invention is applicable; Fig. 2 is a sectional view, on an enlarged scale, of electrical heating apparatus which I employ, and Fig. 3 is a still further enlarged view of one of the heating elements of Fig. 2.

Fig. 1 of the drawing is a schematic arrangement which will be referred to for describing the various steps of the process. Crude oil vapors are directed, substantially at atmospheric pressure, from a crude oil still 3, through the vapor line 4 and an electrically heated conduit 5, to a condenser 6. The conduit 5 is horizontally disposed, so that vapors under low pressure will more readily flow therethrough. From the condenser 6 the condensate passes into a receiving house 7 from whence it is conducted to a benzine tank 8. A pump 9 forces the benzine from tank 8, through a pipe connection 10, into a steam still 11. In the steam still 11 gasoline vapors are formed and pass to a condenser 12. The gasoline passes from the condenser 12 to a tank 13. The pressure, in all parts of the system, is preferably never at any time greatly in excess of atmospheric pressure.

During the early stages of operation, the residue that remains in the steam still after the gasoline has been taken off is kerosene. This kerosene is returned to the crude still 3 for further vaporization, under increased temperature and again passes through the system as above described, under low pressure. In the final stages, a residue or precipitate is left in the steam still 11 which is not capable of further vaporization in the crude still. This material is withdrawn from the steam still and may be used as fuel oil.

While attempts have heretofore been made to crack kerosene, for the purpose of procuring lighter hydrocarbon products therefrom, such cracking has been attempted under high pressures, with the result that incondensable, unsaturated hydrocarbon gases are formed.

Within the conduit 5 I provide electric heaters 15 each of which may consist of a refractory core 16 wound with resistance wire 17 that has terminals 18 that may be connected to any suitable source of electrical power, not shown. An insulating cover 19 of mica or the like surrounds the wire 17 and core 16, while a copper cylinder 20 surrounds the mica covering 19. The insulating cover 19 and the cylinder 20 together form a jacket or protective covering for the wire 17, to shield said wire against direct contact with the vapors and thereby prevent the formation of carbon deposits thereon, and overheating of the vapors that would

otherwise come into contact therewith. The conduit 5 may consist of an iron pipe, and is provided with a copper liner 21. I preferably make the heater covering 20 and the liner 21 of copper since such metal is a better heat conductor than steel or iron, and the vapors which pass through the tubular liner 21 are therefore more effectively and uniformly heated. Adjacent to each end of the liner 21, I provide a deflector 22 which may be also of copper, and is so formed as to direct the vapors into contact with the heaters 15.

In the operation of my system, crude oil 15 is vaporized in the crude still 3 by an any suitable means (not shown). During the early stages of vaporization, it is mainly benzine vapors that pass through the conduit 5 and the other parts of the system above described. Ordinarily these vapors do not require additional heat within the conduit 5. These benzine vapors are condensed in box 6 and the liquid passes to the tank 8 and thence to the steam still 11. The vapors 25 from still 11 pass to the condenser box 12 and are there condensed to form gasoline. During this period of operation, the residue within the steam still 11 is in the form of kerosene which may be returned to the crude 30 still for vaporization.

When the benzine has been distilled from the petroleum in the still 3, additional heat is applied, as is common practice. The vapors which thereafter pass through the conduit 5 are subjected to additional heat and it is then that one or both of the heaters are energized. When these vapors have been condensed and pass into the receiving house 35 7, tests are made periodically to determine the gravity thereof. If the tests show a gravity in excess of that which is desired, heat within the conduit 5 is decreased by reducing the flow of current through the heaters 15, by means of rheostats, (not shown). On the other hand, if the tests show a gravity that is too low, the flow of current through the heaters 15 is increased.

I have found that the temperature of the vapors when passing through the conduit 5 may be increased from 25° F. to 50° F. above the temperature within the crude still 3, with satisfactory results. Thus, if the crude still 3 is operated at temperatures ranging from 325° F. to 625° F., the conduit 5 may be 40 heated from 350° F. to 650° F.

By my arrangement, the temperature

within the conduit 5 may be accurately controlled and quickly changed in accordance with the showing of tests of the liquid in the receiving house. Thus the vapors may be 60 heated sufficiently within the conduit 5, to insure a maximum cracking effect, while if tests of the liquid within the receiving house show the gravity thereof too high and therefore indicate that the temperature within the 65 conduit 5 is too great, with consequent danger of burning and carbonization of the vapor, the heat can be quickly reduced.

Tests made within the receiving house will show when the benzine has all been distilled 70 out of the crude oil. One or both of the heaters 15 is then energized and the temperature of such heaters as well as that of the crude still is thereafter gradually increased 75 as the more volatile materials are distilled from the crude oil.

Tests which I have made with my system show an increase of 15% or more in gasoline yield, over the systems heretofore commonly employed.

I claim as my invention:

1. The combination with a crude oil still and a condenser, of a conduit connecting the same, and a heating element within said conduit, said heating element being provided 85 with a non-corrodible cover.

2. The combination with a crude oil still and a condenser, of a conduit connecting the same, and a heating element within said conduit, the said heating element being provided 90 with a copper cover.

3. The combination with a crude oil still and a condenser, of a conduit connecting the same, a heating element within said conduit, said heating element being provided with a 95 non-corrodible cover, and a confining wall of non-corrodible metal surrounding said heating element but spaced with respect thereto, to permit passage of vapor therebetween.

4. The combination with a crude oil still and a condenser, of a conduit connecting the same, a heating element within said conduit and a jacket surrounding the heating element and spaced from the inner wall of the conduit, said jacket serving to protect the heating element against contact of the vapors from the still.

In testimony whereof I, the said ROSCOE C. KIRWIN, have hereunto set my hand.

ROSCOE C. KIRWIN.
